UNITED STATES PATENT OFFICE.

HORACE L. ROBERTS, OF NEW YORK, N. Y.

DESIGN FOR A JAW FOR TAPE-COUPINGS.

SPECIFICATION forming part of Design No. 29,728, dated November 29, 1898.

Application filed November 2, 1898. Serial No. 695,327. Term of patent 7 years.

To all whom it may concern:

Be it known that I, HORACE L. ROBERTS, a citizen of the United States, residing at New York city, (Manhattan,) county and State of New York, have invented and produced a new and original Design for Jaws for Tape-Couplings, of which the following is a specification, reference being had to the accompanying drawings, in which—

10 Figure 1 is a perspective view of my newly-designed jaw for tape-couplings; Fig. 2, a cross-section of the same.

15 The leading feature of my design consists of a jaw for tape-couplings, provided with a pair of diverging shanks having parallel ends

and inwardly-projecting lips back of such ends.

The shanks *a* diverge from a rounded acute angle *b* and terminate in parallel ends *c*. Back of such ends lips *d* project inwardly 20 from the shanks. The rounded angle *b* is provided with a number of perforations *e*.

What I claim is—

The design for the jaw of a tape-coupling, substantially as herein shown and described. 25

HORACE L. ROBERTS.
